Primary Examiner — Mark Goodwin*(74) Attorney, Agent, or Firm* — Knobbe, Martens, Olson & Bear, LLP(57) **CLAIM**

The ornamental design for an integrated stiffener, as shown and described.

DESCRIPTION

FIG. 1 is a front perspective view of the integrated stiffener of the present design;

FIG. 2 is a front elevational view thereof, the rear elevational view being a mirror image thereof;

FIG. 3 is a right side elevational view thereof, the left side elevational view being a mirror image thereof;

FIG. 4 is a top plan view thereof; and,

FIG. 5 is a bottom plan view thereof.

Broken lines are used to illustrate features of the integrated stiffener which form no part of the claimed design.

1 Claim, 4 Drawing Sheets
